Assistant Examiner — Dustin Andrew Griffith

(57) **CLAIM**

The ornamental design for a backpack, as shown and described.

DESCRIPTION

FIG. 1 is a front, top and right-side perspective view of a backpack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is an enlarged view, of circled portion 9, of FIG. 2, thereof;

FIG. 10 is an enlarged view, of circled portion 10, of FIG. 4, thereof;

FIG. 11 is an enlarged view, of circled portion 11, of FIG. 6, thereof; and,

FIG. 12 is an enlarged view, of circled portion 12, of FIG. 7, thereof.

The broken lines throughout the drawing figures depict portions of the backpack that form no part of the claimed design.

The dot-dash broken lines depict the boundaries of the FIGS. 2, 4, 6, 7, and 9-12 enlargement that forms no part of the claimed design.

1 Claim, 12 Drawing Sheets
